AUTOMATIC GATE

William S. Snelgrove, Milledgeville, Ga.

Application June 29, 1933, Serial No. 678,275

6 Claims. (Cl. 39—67)

This invention relates to automatic gates such as are arranged to open and close upon the approach and departure of a vehicle. More especially the invention relates to the type of gates used on farms, highways and railroads and the like.

One important object of the invention is to provide an improved construction of gates of this description.

A second important object of the invention is to provide a novel and improved construction of gate which may have its operative parts constructed economically of rods, pipes, and the like, bent and shaped to suit their use.

A third important object of the invention is to provide a gate of this class having a gate track one end of which is raised by a spring to open the gate so that the track is given a vibratory movement assisting the movement of the gate along the track.

A fourth important object of the invention is to provide a novel arrangement of latch means for releasably holding the gate in its open and closed positions, the latch means being arranged to release by tilting of the gate track in one direction and the other.

A fifth important object of the invention is to provide a novel spring means for giving the gate its initial opening and closing movements, the spring means being tensioned by the inertia of the gate itself in opening and closing.

With the above and other objects in view, the invention consists in general of certain novel details of construction hereinafter fully described, illustrated in the accompanying drawings, and specifically claimed.

In the accompanying drawings, like characters of reference indicate like parts in the several views, and

Figure 1 is a front elevation of the invention with the gate in open position.

Figure 2 is a side elevation thereof.

Figure 3 is an enlarged side elevation, partly in section, of certain of the operating parts of the invention.

Figure 4 is a section on the line 4—4 of Figure 3.

Figure 5 is a section on the line 5—5 of Figure 3.

Figure 6 is a section on the line 6—6 of Figure 3.

Figure 7 is an enlarged detail elevation of a portion of the gate track and an upper corner of the gate.

Figure 8 is a section on the line 8—8 of Figure 7.

Figure 9 is a detail elevation of the upper end of a telescoping gate part used herewith and showing the connection of the track thereto.

Figure 10 is an enlarged section on the line 10—10 of Figure 5.

Figure 11 is a detail elevation showing a gate post to which the track is pivoted.

Figure 12 is a section on the line 12—12 of Figure 11.

Figure 13 is a detail elevation showing the latch for holding the gate open.

Figure 14 is an enlarged detail elevation of a portion of the linkage at the right end of Figure 2.

Figure 15 is a view similar to Figure 14 but showing a portion of the left end of Figure 2.

Figure 16 is an enlarged section on the line 16—16 of Figure 1.

Figure 17 is an enlarged section on the line 17—17 of Figure 1.

Figure 18 is a detail showing portions of the gate and the spring for starting the closing movement of the gate.

While the invention is capable of a wide variety of uses and may be constructed with a great variation in detail and in many embodiments, one embodiment suitable for use as a farm field gate is shown in the accompanying drawings as illustrating the general principles of construction and operation of gates in accordance with the invention. It is, however, to be understood that the invention is not to be restricted in form, proportions, and details by reason of but one embodiment being shown.

In the embodiment here shown it is to be noted that most of the various parts are constructed of pipes or rods, thus assuring great economy in the production of these gates.

In this embodiment there is provided a part 10 of piping or tubing which is supported vertically on a suitable foundation. Spaced from this part is a second part which consists of a lower member 11 of piping or tubing and an upper tubular member 12 which is slidably mounted in the upper part of the member 11 and is supported on a coiled compression spring 13 which is held in the lower part of the member 11. The upper member is thus constantly urged to elevated position. An I beam track 14 has one end connected to the upper end of the post 10 by a pivot pin 15 and has connection with the upper end of the member 12 by a pin and slot connection 16. The telescoping member 12 is so proportioned that, in its raised

position, it holds the track inclined downwardly towards the post 10 and in its depressed position it holds said track inclined downwardly to the other post and thus inclined downwardly from 5 the post 10.

The gate itself has a frame consisting of a piece of pipe 17 bent to inverted U-shape and having the lower ends of its legs connected by a pipe 18. Also a pipe 19 connects the legs near the top and between the pipe 18 and the pipe 19 the frame is filled with a stout wire netting or other suitable material. This gate is supported from the track by a hanger frame preferably constructed in the following manner. The sides of the frame are formed by two pairs of hangers 20 which have their lower ends securely fastened to the upper frame member of the gate. These hangers, at their upper ends, are arranged so that each side has one hanger on one side of the track and the other hanger on the opposite side of said track. The upper ends of the hangers on each side of said track are connected by ties 21 and between the ties are ball bearing rollers 22 which run on the track 14 and thus enable the frame and gate to travel easily along said track. A cover plate 23 covers the space between the ties 21 and protects the rollers from the weather. Diagonal braces 24 connect the corners of the hanger frame and serve to stiffen and brace this frame against distortion.

In connection with the gate proper there is preferably used a plate 25 on each face of the wire mesh. This plate may be of any desired color form, and material. For instance, part of the plate may be highly reflective and part may be painted red. Thus, when the gate is closed, an approaching motorist will clearly see, in the daytime, a red danger signal and, at night, will have the light from his headlights reflected from the polished part of the plate. He is thus warned to slow down on approaching the gate. A yoke 26 is fixed to the ground adjacent the free end of the gate, when closed, and stay wires 27 connect the arms of this yoke with the post 10. This yoke is to prevent hogs and the like from forcing that end of the gate away from the fence in connection with which it is used, in order to escape from the enclosure. It will here be noted that when the member 12 is elevated the gate will roll toward the post 10 and when said member 12 is depressed the gate will move toward the post 11. A latch 28 is pivoted to the post 10 and the rear leg of the member 17 is provided with a keeper 29 which is engaged by said latch when the gate is fully opened. A spring 30 yieldably holds the latch for engagement with the keeper. Fastened to the post 10 is one end of a leaf spring 31 which is engaged and stressed by the gate member 17 as the gate moves to fully opened position, the inertia of the moving gate being sufficient to effect this stressing of the spring. Thus, when the latch engages the keeper, the spring is held under stress. The arrangement of the latch is such that the spring normally holds it against a keeper 32 in such position that, when the post member 12 is nearly depressed, the keeper releases from the latch. As soon as this occurs the spring 31 acts to start the gate on its travel to closed position. A similar, but inverted latch, 33 is pivoted on the front leg of the gate and is held normally against a keeper 34 by a spring 35. In the post member 11 is a pair of oppositely disposed and longitudinally extending slots 36 through which extend the ends of a cross piece 37, which cross piece also extends through the lower

part of the member 11 and is notched on its bottom edge to fit the member 11, being held in place by a wedge or key 38, as clearly shown in Figure 10. This cross piece, when the member 11 is in depressed position, forms a keeper for the the latch 33, as shown in Figure 5. On the front leg of the member 17 is fixed one end of a leaf spring 39 which engages at its other end against the post member and is held in stressed condition by the engagement of the latch 33 with the cross piece 37. Obviously, upon the cross piece rising the latch will be released and the spring 39 will start the gate on its travel toward the post 10. Each of these springs 31 and 39 is provided on its free end with a leg 40 adapted to enter a hole 41 in the member with which the spring engages so as to hold the gate steady in both open and closed positions.

Mounted at each side of the gate and a suitable distance from the gate is a rocking member 42 20 provided with cranks 43 which are adapted to be engaged by the wheels of a vehicle in passing to and from the gate, each member 43 being rocked in one direction as a vehicle moves toward the gate and in the opposite direction as the vehicle 25 moves away from the gate. On these rocking members at the left and right of Figure 2, respectively, are rock arms 44 and 45. Secured to the lower part of the post member 11 is a fulcrum yoke 46 having oppositely disposed arms to the 30 ends of which bent levers 47 are pivoted intermediate their ends. The upper ends of these bent levers are connected by links 48 with the ends of the cross piece 37. Forks 49 are pivoted to the lower ends of the respective levers 47 and 35 are fixed in the ends of pipes 50 in the opposite ends of which side rods 51 which have their outer ends pivoted to the respective rock arms 44 and 45. The pipes 50 are provided with slots 52 and 40 keys 53 carried by the inner ends of rods 51 which move in these slots. The arrangement of the keys and slots is such that, upon the rocking of either rocking member and rock arm away from the gate the telescopic link formed by the pipe 50 and the rod 51 of that side of the gate will pull the lower end of the lever to which that link is 45 attached away from the post as in Figure 3 and thus effect depression of the cross piece 37 and consequently of the track at the end connected to the post member 11. This, of course, compresses the spring 13. Also, the other lever 47 will move and force the pipe 50 to which it is attached outwardly to telescope on its rod 51, thus leaving the remaining rocking member 42 at rest. In 50 order to hold the cross piece down there is provided a latch 54 which is pivoted intermediate its ends to the fulcrum yoke 46. The upper end of this latch engages a key or keeper 55 which is carried by the member 12 and works in a vertical slot 56 formed in the member 11. This latch is 55 normally held in position to engage its keeper by a spring 57 which has one end connected to the lower end of the latch and its other end connected to the outer end of a bracket 58 carried by the post member 11. A connecting piece 59 is 60 also pivoted to the lower end of the latch member and on each end of this connecting piece is fixed a pipe 60 in the outer part of which lies a rod 61, each rod and pipe thus forming a telescopic link. The outer ends of the rods 61 are 65 connected respectively to an arm 62 formed on the rock arm 44 and to a rock arm 63 carried by the other member 42. The arrangement of the telescopic links formed by the pipes 60 and rods 61 is such that when either member 42 is rocked 70

towards the gate the latch 54 will be moved to release the keeper 55, while movement of either member 42 in the opposite direction from its normal position will not affect the latch. To this end, each member 60 is provided with longitudinal slots 64 in which works a key 65 carried by the corresponding member 61. Between each key and an adjustable collar 66 on the respective pipe 60 is a coiled compression spring 67 which, 5 at the left of Figure 2, holds the key 65 substantially central of the slots 64 and at the right of Figure 2 holds the key in the outer ends of said slots.

In order to assist in holding the cranks 43, normally vertical springs 67 are provided, each of which has one end attached to a collar 68 adjustably secured on a respective pipe 60. The remaining end of the left hand spring is attached to an arm 69 projecting from the rock 20 arm 44 while the remaining end of the right hand spring is attached to a rock arm 70 on the right hand rocking member 42.

In this embodiment, the gate is normally closed with the spring 13 compressed. On the 25 approach of the vehicle, the rocking member at the side of the gate from which the vehicle is approaching is rocked toward the gate. This effects, in the manner previously described, the release of the latch 54, so that the member 12 connected to the track at the end and carried thereby is thrown upwardly by the spring 13. At the same time, the latch 33 is released and the spring 39 starts the gate down the track, its movement being assisted by the vibratory effect of the 30 spring 13. The gate opens and catches against the post 10. The vehicle passes through the open gateway and engages the other rocking member 42 to rock it away from the gate. This actuates the linkage, in the manner already described, which 35 depresses the member 12 and unlatches the gate from the post 10 to allow the spring 31 to start it down the track which is now inclined downwardly from the post 10. Consequently, the gate closes and is latched in closed position ready for 40 a subsequent operation.

Obviously, if the gate is used as a railway crossing gate it will be normally open, being closed by the approach of a train and opened by the passage of the train beyond the crossing. Naturally, 45 in this case the linkage for tripping the latch 54 and for depressing the post member 12 will be somewhat changed in detail but the principles of construction and operation will remain the same.

50 There has thus been provided a highly effective device of the kind described and for the purpose specified.

It is obvious that changes may be made in the 55 form, construction, and proportions of the invention without departing from the material substance of the same. It is not, therefore, desired to confine the invention to the embodiment here shown and described, but it is desired to include all such as come within the 60 scope of the appended claims.

What is claimed is:

1. In an automatic gate device, a gate post, a supporting track having one end pivoted to said gate post, a second gate post including a 65 lower and an upper member, telescopically connected and having the remaining end of the track carried by the upper member, said upper member being arranged when elevated to incline the track downwardly towards its pivotal 70 end and when depressed to incline the track in

the opposite direction, a gate adapted to roll on said track, between said posts, means urging said upper member to elevated position, latch means releasably holding the upper member in depressed position, and vehicle actuated means 5 operatively connected to said latch means and upper member and movable into one position to release the latch and allow the upper member to be elevated by the passage of a vehicle in one direction, said vehicle actuated means being 10 movable into a second position to depress said upper member by the passage of a vehicle in the opposite direction.

2. In an automatic gate device, a gate post, a track having one end pivoted to said post, a 15 second gate post consisting of a tubular lower member and an upper member vertically slidable in the lower member and having an end of the track attached thereto, the movement of the upper member being such as to incline the track 20 in opposite directions, a gate adapted to roll on the track, a spring in said tubular member urging the upper member to raised position, said lower member having a passage therethrough, a cross 25 piece carried by the upper member and projecting through said passage, a keeper carried by the upper member, a latch adapted to engage said keeper, vehicle actuated means movable in two directions, an operative connection between said means and latch to release the keeper 30 as the means is moved in one direction, and a second operative connection between said means and the cross-piece arranged to depress the upper post member upon said means being moved in the opposite direction.

3. In an automatic gate device, a gate post, a gate supporting track having one end pivoted to the upper end of said post, a second gate post consisting of a tubular lower member and an upper member vertically slidable in the upper 40 part of the lower member and having the remaining end of the track attached, the movement of the upper member between its upper and lower positions being such as to incline downward towards and downwardly from its pivot respectively, a gate adapted to roll on said track from one post to the other as the track is tilted, a spring in said tubular member urging the upper member to raised position, said lower member having oppositely disposed slots, a cross piece 45 carried by the upper member and projecting through said slots, latching mechanism associated with the upper member and adapted to hold the same in its lower position, a rockable member arranged to be rocked by a moving vehicle toward and from the gate respectively, a linkage connecting the rockable member and the latching mechanism to release the latter upon movement of the rocking member in one direction, and a linkage connecting the rocking member and cross piece to depress the latter upon movement of the rocking member in the opposite direction.

4. In an automatic gate device, a gate post, a 65 gate supporting track having one end pivoted to the upper end of said post, a second gate post consisting of a tubular lower member and an upper member vertically slidable in the upper 70 part of the lower member and having the remaining end of the track attached, the movement of the upper member between its upper and lower positions being such as to incline downward towards and downwardly from its pivot respectively, a gate adapted to roll on said track 75

- from one post to the other as the track is tilted, a spring in said tubular member urging the upper member to raised position, said lower member having oppositely disposed slots, a cross piece carried by the upper member and projecting through said slots, latch mechanism associated with the upper member and adapted to hold the same in its lower position, a rockable member arranged to be rocked by a moving vehicle toward and from the gate respectively, a pair of telescopically arranged members connecting said rockable member and latch mechanism to operate the latter as the rocking member moves in one direction, spring means between the last mentioned telescopic members and yieldably holding said members in normally telescoped relation, and a linkage connecting the rocking member and cross piece to depress the cross piece upon movement of the rocking member in the opposite direction.
5. In an automatic gate device, gate posts, a gate mounted to travel between the posts, means for causing the gate to travel, means carried by the gate and a post for latching the gate against travelling movement, means for releasing said latching means, and a spring interposed between the gate and a post for imparting an initial
- 10
- 15

movement to the gate upon operation of the travel causing means.

6. In an automatic gate device, a gate post, a track having one end pivoted to said post, a second gate post including a tubular lower member and a depressible member vertically slidable in the lower member and having an end of the track attached thereto, the movement of the upper member being such as to incline the track in opposite directions, a gate adapted to roll on said track, a spring in said tubular member urging the upper member to raised position, a cross piece carried by the upper member, latching mechanism associated with said upper member and adapted to hold said member in depressed position, vehicle actuated means movable in two directions, an operative connection between the vehicle actuated means and said latching mechanism to release said depressible member when said vehicle actuated means is moved in one direction and an operative connection between said vehicle actuated means and the cross piece arranged to depress the depressible member when the vehicle actuated means is moved in the other direction.
